UNITED STATES PATENT OFFICE

JAMES A. McGREGOR, OF CLEVELAND, OHIO

PROCESS OF FLANGING SHEET METAL

Original applications filed October 8, 1926, Serial No. 140,362, and March 7, 1928, Serial No. 259,665.
 Divided and this application filed March 7, 1928. Serial No. 259,664.

This invention relates to the flanging of sheet metal, and more particularly to a method of forming edge flanges in sheet metal.

5 This application is a division of my co-pending applications for corner die, Serial No. 140,362 filed October 8, 1926, and for die for flanging sheet metal, Serial No. 259,665, filed March 7, 1928, and is a continuation in 10 part of my copending application for process of making flanged sheet metal articles, Serial No. 162,482, filed January 21, 1927.

Previously, to form edge, such as peripheral, flanges in sheet metal, for example, in 15 the manufacture of table tops, washtub covers, pans and the like, it has been customary to form such peripheral flanges by a single operation by providing suitable die apparatus for each shape and size of article to be formed. 20 While this method of manufacture has been satisfactory where the number of articles of a particular size to be formed has been sufficient to warrant the construction of special die mechanism, said practice has been in- 25 flexible in operation and has been too expensive for the flanging of articles of a wide range of sizes and shapes in any but extremely large quantities.

An object of this invention is to provide an 30 advantageous method of flanging sheet metal. Other objects are to provide an advantageous method for forming edge, such as peripheral, flanges in sheet metal; to provide a 35 method whereby flanged articles of a wide variety of shapes and sizes may be economically manufactured; and to provide for the formation of beaded edges or other surface configurations simultaneously with the flanging operations.

Other objects of the invention will be apparent to those skilled in the art from the written disclosures herein made and from the appended drawings, wherein:

45 Figure 1 is a plan view of a substantially

rectangular sheet metal blank having one corner flange formed therein;

Fig. 2 is a plan view of a sheet metal blank having rounded corners and having a corner flange and beaded edge portion formed 50 therein;

Fig. 3 is a plan view of the sheet metal blank shown in Fig. 2 showing four corner flanges and corresponding beaded edge portions formed therein;

Fig. 4 is a plan view of the sheet metal shown in Figs. 2 and 3, the portions intermediate the corner flanges having been flanged and beaded whereby to form a peripheral flange and peripheral beaded edge; 55

Fig. 5 is a fragmentary vertical section taken on line 5—5 of Fig. 1;

Fig. 6 is a fragmentary vertical section taken on line 6—6 of Fig. 2;

Fig. 7 is a plan view of a sheet metal blank 65 having a corner flange formed therein, said flange having a depending portion and a lateral portion;

Fig. 8 is a fragmentary vertical section taken on line 8—8 of Fig. 7;

Fig. 9 is a plan view of sheet metal having four corner flanges formed therein, said flanges together forming a substantially rectangular peripheral flange;

Fig. 10 is a fragmentary plan view of sheet 75 metal having end flanges of irregular shape formed therein;

Fig. 11 is a fragmentary plan view of sheet metal having substantially rectangular end flanges formed therein, each end flange comprising a pair of corner flanges;

Fig. 12 is a plan view of sheet metal having substantially rectangular end flanges formed therein, said end flanges together 80 forming a substantially rectangular peripheral flange;

Fig. 13 is a plan view of sheet metal having a pair of partially peripheral curved flanges formed therein, said flanges together form- 90

ing a substantially elliptical peripheral flange; and

Fig. 14 is a plan view of sheet metal having diverging sides, end flanges of non-uniform size being formed therein.

In this application, the term "curved flange" will be understood to include flanges of either regular or irregular contour and flanges having straight portions, as well as flanges having two or more adjacent straight portions angularly disposed.

My invention contemplates primarily the formation in sheet metal of a continuous edge flange, the formation of said flange including the step of forming a partially peripheral curved flange. My invention, of course, may be carried out in various ways, certain of which will be described hereinafter. In carrying out my invention, die apparatus such as disclosed in my hereinbefore mentioned copending applications Serial Nos. 140,362 and 259,665, may be advantageously employed.

One advantageous application of my invention is in the formation of a substantially rectangular sheet metal article having a depending peripheral flange, such as, for example, a table top. Thus, a depending corner flange 1 may be formed in a substantially rectangular sheet metal blank 2 (Fig. 1). An excess metal portion 3 (Fig. 3) may be subsequently removed as by shearing. It is frequently convenient to employ a sheet metal blank 4 having rounded corners, as in Fig. 2, or otherwise suitably shaped, to avoid the formation of excess metal portions. By suitable die apparatus, a corner flange 5 may be formed simultaneously with a beaded edge portion 6, as in Fig. 2, or a corner flange such as 7, (Figs. 7 and 8), having a depending portion 8 and a lateral portion 9 may be formed in the blank 10. The cross-sectional shape of the first corner flange (Figs. 5, 6, and 8) may thus be of widely varying character, and is not limited to the specific examples given. The depending portion of a flange may be bent, of course, to any desired angle to the plane of the sheet metal blank.

Subsequently to the formation of the first corner flange, as discussed in the previous paragraph, the remaining corner flanges may be formed, together with beaded portions, as indicated in Fig. 3. Unflanged portions 11 and 12 intermediate the corner flanges 5 may then be formed subsequently by any suitable well known apparatus whereby to complete the formation of a peripheral flange 13 and peripheral beaded portion 14, as shown in Fig. 4. The order of the steps outlined for the formation of the flange 13 may, of course, be varied. Thus, two corner flanges 5 may be formed, an intermediate portion 11 or 12 flanged, another corner flange 5 formed, etc. However, I find it convenient to form the four corner flanges and then subsequently to

flange the portions intermediate said corner flanges, though my invention is not limited to this sequence of steps.

In certain cases, the sheet metal 15 and a corner flange 16 formed therein (Fig. 9) may bear such relation to each other as to size that no intermediate unflanged portions will remain after the formation of the corner flanges in the sheet metal. Thus, the corner flanges 16 (Fig. 9) are shown as mutually overlapping as indicated by the arrows 16-16, whereby it is obvious that a peripheral flange is formed merely by the formation of the corner flanges 16. Beaded edge portions 17 may be formed simultaneously with the corner flanges 16.

A relatively long and narrow flanged article may be formed by forming the corner flanges 18 (Fig. 11) and subsequently flanging any unflanged intermediate portions between said corner flanges. In Fig. 11 the corner flanges at each end of the sheet metal blank 19 are shown as of such size, as indicated by the arrows 18-18, as to form the continuous end flange 20, the corner flanges 18 for this purpose abutting, or overlapping as indicated.

Instead of forming corner flanges, I may find it convenient to form end flanges each including more than one corner. Thus, in Fig. 12 I have shown the end flanges 21 formed in the sheet metal blank 22. The said end flanges may abut, or may overlap, as indicated by the arrows 21-21, to form together a peripheral flange. Where the sheet metal is relatively long, any unflanged portions intermediate the end flanges 21 may be subsequently flanged.

While the above specific illustrations have related to rectangular sheet metal articles, it is obvious that my invention applies likewise to the formation of sheet metal articles of any polygonal shape. The sides of the corner flanges may be disposed at any desired angle to each other and the end flanges may, in general, include any desired number of corners.

The partially peripheral curved flanges contemplated by this invention furthermore may be of regular or irregular shape and may include straight and/or curved portions. In Fig. 10 I have illustrated the formation of end flanges of irregular shape, the end flanges 23 being shown as formed in the sheet metal blank 24. The unflanged portions 25 intermediate the end flanges 23 may be flanged, if desired, to complete the formation of a peripheral flange. In certain cases, of course, the end flanges 23 may abut or overlap in the manner shown in Fig. 12 to form by themselves a completely peripheral flange.

In Fig. 14 I have illustrated the flanging of a sheet metal blank 26 having divergent sides, said sheet metal having formed therein the non-uniformly sized curved end flanges 27 and 28. Suitable die apparatus may be pro-

vided for the formation of each of said end flanges. Unflanged edge portions intermediate the end flanges may be flanged to complete a peripheral flange.

5 In Fig. 13 I have illustrated the formation of a substantially elliptical article, the peripheral flange 29 comprising the overlapping end flanges 30.

In Figs. 10 to 14, inclusive, the articles 10 illustrated are shown as having beaded edge portions associated with the flanges, which beaded portions may be omitted or not, as desired.

The foregoing examples illustrate certain 15 of the applications of my invention to the formation of flanged articles. The article to be formed may embody a completely peripheral flange or a flange of less than peripheral extent. My invention, furthermore, is not 20 limited to articles of any particular size or shape.

By my invention I have thus provided an 25 extremely flexible method of forming flanged articles, whereby by the use of die apparatus arranged to form partially peripheral curved flanges, articles of a wide variety of shapes and sizes may be formed. My invention thus lends itself to the economical production of 30 relatively small quantities of articles of a given size, as well as to larger scale production.

Furthermore, it is to be understood that the 35 particular forms of apparatus shown and described, and the particular procedure set forth, are presented for purposes of explanation and illustration and that various modifications of said apparatus and procedure can be made without departing from my invention as defined in the appended claims.

40 What I claim is:

1. The method of forming a sheet metal article having a completely peripheral depending flange, which comprises forming a depending corner flange in a piece of sheet 45 metal, forming additional depending corner flanges, and forming depending flanges intermediate said corner flanges to thereby form a completely peripheral depending flange.

50 2. In the manufacture of sheet metal articles having depending peripheral flanges, the steps which comprise forming a depending corner flange in sheet metal, forming a second depending corner flange in said sheet metal, and subsequently forming a depending flange intermediate said corner flanges whereby to form a continuous depending flange.

55 3. The method of forming a sheet metal article having a continuous peripheral depending flange requiring no trimming, which method comprises forming a depending corner flange in a piece of sheet metal having rounded corners, forming additional depending corner flanges, and forming depending flanges intermediate said corner flanges.

4. The method of forming a completely peripheral depending flange and beaded edge in sheet metal which comprises forming a depending corner flange in said sheet metal and simultaneously forming a corner beaded portion, forming additional depending corner flanges and corner beaded portions, and forming depending flanges and beaded edges intermediate said corner flanges and corner beaded portions.

5. The method of forming a sheet metal article having a continuous peripheral beaded edge and continuous peripheral depending flange requiring no trimming, which method comprises forming simultaneously a depending corner flange and corner beaded portion in a piece of sheet metal having rounded corners, forming additional depending corner flanges and corner beaded portions, and forming depending flanges and beaded edges intermediate said corner flanges and corner beaded portions.

6. The method of forming a substantially rectangular sheet metal article having a smooth depending completely peripheral flange and a peripheral beaded portion, which comprises forming in a substantially rectangular piece of sheet metal a smooth depending rectangular corner flange, simultaneously forming a corner beaded portion, forming in successive operations three more rectangular depending corner flanges and corner beaded portions, and subsequently forming depending flanges and beaded portions intermediate said corner flanges whereby to form a smooth completely peripheral depending flange and a peripheral beaded portion.

7. The method of forming a sheet metal article having a completely peripheral depending flange which comprises forming by a single operation a depending corner flange in a piece of sheet metal, in like manner forming additional corner flanges in said sheet metal, and subsequently flanging the portions intermediate said corner flanges to form a completely peripheral depending flange.

8. In the formation of a polygonal flange in sheet metal, the steps of forming in said sheet metal a partially peripheral curved flange including at least one corner, and subsequently forming in said sheet metal another partially peripheral curved flange including at least one corner.

9. In the formation of a completely peripheral flange in sheet metal, the steps of forming in said sheet metal a partially peripheral curved flange, forming at least one more partially peripheral curved flange in said sheet metal, and flanging the sheet metal intermediate said curved flanges to complete the formation of a completely peripheral flange in said sheet metal.

10. In the formation of a completely pe-

ripheral flange in sheet metal, the steps of forming in said sheet metal a plurality of partially peripheral curved flanges, and flanging any unflanged portions therebetween to complete the formation of a completely peripheral flange in said sheet metal.

11. In the formation of a continuous flange in sheet metal, forming in said sheet metal a plurality of flanges arranged to produce together a continuous flange of greater linear extent than any of the component flanges, at least one of said component flanges being a partially peripheral curved flange.

In testimony whereof I affix my signature.
